UNITED STATES PATENT OFFICE.

JOHN F. DAVEY, OF BEVERLY, MASSACHUSETTS, ASSIGNOR TO UNITED SHOE MACHINERY COMPANY, OF PATERSON, NEW JERSEY, AND BOSTON, MASSACHUSETTS, A CORPORATION OF NEW JERSEY.

PEGGING-MACHINE.

No. 800,724

Specification of Letters Patent.

Patented Oct. 3, 1905.

Original application filed May 28, 1900, Serial No. 18,239. Divided and this application filed October 19, 1901. Serial No. 79,317.

To all whom it may concern:

Be it known that I, JOHN F. DAVEY, of Beverly, county of Essex, and State of Massachusetts, have invented an Improvement in Pegging-Machines, of which the following description, in connection with the accompanying drawings, is a specification, like letters on the drawings representing like parts, this application being a division of an application filed by me May 28, 1900, Serial No. 18,239.

The present invention relates to a pegging-machine for pegging boots and shoes; and the machine embodying the invention is especially designed for pegging the heel portions only, it being practicable to simplify the construction and arrangement of the machine when used for this purpose only, since the horn can be substantially straight and non-rotatable, as the tip of the horn does not have to be inserted in the shoe under the forward part of the upper. Furthermore, it is very desirable to fasten heel-seats—that is, attach the heel portion of the soles—with wooden pegs, as this facilitates the subsequent operation of fastening the heels themselves and prevents the liability of accidental injury due to the fact that the nails which fasten the heels may be diverted and turned back or driven out through the heel by contact with metallic fastenings, if such metallic fastenings have been used.

By employing a substantially straight vertical horn it is practicable to simplify to a great extent the operating mechanism for the peg cutting or trimming devices, the said cutting devices being operated by means of a single reciprocating rod without the intermediate connections which are necessary with an inclined rotatable horn. It is necessary, however, that the said rod and the parts of the cutting device which are connected therewith should be so positioned with relation to the awl and peg driving mechanism that the said awl in the punching operation shall clear the same, and to this end the cutting device is of novel construction and arrangement and comprises a cutter or pair of cutters offset with relation to the shanks or jaws by which they are carried, so that the awl in passing down between or adjacent to the said cutters will not interfere with the said shanks.

Figure 1 is an elevation, partly in section, of the lower portion of the machine, showing

the horn and the actuator for the cutting devices. Fig. 2 is a vertical section on the line x^2 of Fig. 3. Fig. 3 is a rear elevation of the upper portion of the horn, the cutter-jaws being shown in dotted lines as open. Fig. 4 is a view similar to Fig. 3, certain covering-plates being omitted to show the cutter mechanism, the cutter-jaws being shown in full lines as closed; Fig. 5, a top plan view of the horn top or cover; Fig. 6, a perspective view of the under side of the same; Fig. 7, a perspective view of the cutting-blades, and Fig. 8 a perspective view of the cutting jaws or shanks.

The horn a is herein shown as a substantially straight vertical member non-rotatably mounted in the horn-support A^2 , which support is suitably connected with the frame A of the machine, the said horn being normally pressed upward by means of a spring a^3 , so as to hold the work supported thereon between the horn top or cover b and the nose-plate B at the forward part of the head of the machine.

The awl, peg-driving mechanism, &c., which are located and operated in the head of the machine, may be of any suitable or usual construction, and the head of the machine is not herein shown, except that a portion of the nose-plate is illustrated in Fig. 1 to show the relation of the head of the machine to the horn a , the said nose-plate being like that of the head shown and described in Letters Patent of the United States No. 581,066, granted April 20, 1897, to Davey and Ladd.

To insert or remove the work, the horn a is capable of being depressed with relation to the nose-plate B and is connected for this purpose with a horn-depressing yoke a^3 , connected with a suitable treadle a^4 .

The machine is provided with a cutting device operating in the top of the horn a below the cover b , the said cutting device being herein shown as a pair of cutter-blades c , Figs. 4 and 7, mounted on the tops of shanks or jaws c^2 , which have concave and convex bearing-surfaces c^3 and c^4 co-operating with corresponding bearing-surfaces a^5 and a^6 in the top of the horn, the bearing-surface a^5 being shown as formed on a pin held in position in the top of the horn by means of a nut a^7 . The cutter-jaws c^2 are arranged to operate like a pair of pliers, so as to separate the cutters c when the awl descends and to close the cutters together after

the peg is driven, so as to cut off the projecting end thereof, the said jaws being shown as provided with overlapping portions c^5 , having oppositely curved slots or openings c^6 , through which extends a transverse member d , carried by a vertically-reciprocating rod d^2 . The reciprocating movement of the said rod d^2 is provided for by means of cam-actuating devices or rockers d^3 , Fig. 1, which are connected with the depressing-yoke a^3 and operated by means of a link d^4 , connected with one end of an elbow-lever d^5 , pivoted in the frame A, the other end of said lever being connected, by means of a rod d^6 , with actuating mechanism in the head of the machine. The actuating mechanism for the rod d^2 is substantially the same as that shown and described in an application for Letters Patent of the United States filed March 24, 1900, Serial No. 10,020, by Ronald F. McFeely, and forms no part of the present invention, the only difference being that the cam-surfaces are reversed, since the rod d^2 extends directly to the cutters and causes the cutting operation by its downward movement instead of by its upward movement, as in the construction shown in the McFeely application, where there is an intermediate connection.

The transverse member d aforesaid extends across from one member to the other of a forked slide d^7 , Fig. 2, connected to the end of the rod d^2 , the said slide having a suitable bearing in the upper portion of the horn a , which bearing is herein shown as a vertical channel cut in the said horn. The slide d^7 is held in position by means of a plate d^8 , secured to the horn, as by screws d^9 , thus holding the parts securely in position without preventing the ready removal thereof for repairs. At the upper portion of the plate d^8 is a small supporting-socket for one end of the member a^5 , which affords the inner bearing for the cutter-jaws c^2 . The overlapping shanks of the cutter-jaws extend between the forked members of the slide d^7 , the whole mechanism thus being compact and at the same time properly held in position. The horn top or cover b is provided with an opening b^2 in line with the awl when the said awl is performing its operative stroke, so that the awl can penetrate the material and pass through the said opening without injuring the horn-top or work-supporting surface. Below the said opening the said top is provided with a channel b^3 , Fig. 6, substantially equal in width to the width of the cutters c , which fit in the said channel and travel back and forth in the same as the jaws c^2 open and close.

The cutters c are shown as provided with transverse channels c^8 , adapted to fit tongues c^9 at the tops of the jaws c^2 , the top or cover b constituting the means for holding the said cutters c in position. The said cover b is shown as secured to the horn by means of screws b^4 and is laterally positioned by means

of a tongue b^5 , which fits a corresponding channel at the top of the horn.

In order that the awl may descend when the cutter-jaws c^2 are separated without interfering with the said cutter-jaws, the latter are shown as offset at their upper ends, as best indicated in Figs. 2 and 8, so that while the cutter-blades c themselves are directly below the opening b^2 the jaw-shanks c^2 are in front of the said opening and out of alignment with the awl, which can thus descend the required distance without striking or injuring any part of the mechanism.

The cover-plate d^8 does not extend wholly to the top of the horn, so that a lateral opening is left below the opening b^2 , through which opening the severed peg-tips are free to drop out, the surface of the plate d^8 being scooped out or beveled, as shown at d^{10} , to afford a deflecting-surface for the peg ends.

As herein shown, the horn is open at the back for some distance, so that the parts within the same may be readily accessible, the opening being closed after the machine is assembled by means of a plate a^8 .

It is to be understood that the term "pegging-machine" as hereinbefore used is intended to include mechanism for driving fastenings of any kind or material, and, further, that it is not intended to limit the invention to the specific construction and arrangement herein shown and described, since modifications may be made without departing from the invention.

I claim—

1. In a pegging-machine, the combination with the awl; of a substantially straight horn in alignment with the awl and having an opening at the top for the awl; and a cutting device operating in said horn and having a main portion out of the path of the awl and a cutting portion projecting toward the opening and into the path of the awl, as set forth.

2. In a pegging-machine, the combination with the awl; of a substantially straight horn in alignment therewith; a cutting device comprising a jaw having a pivotal support in the top of the said horn, said support projecting toward but not into the path of the awl; and a cutting-blade carried by said jaw and projecting into the path of the awl.

3. In a pegging-machine the combination with a straight horn; of an awl in alignment therewith; a top or cover having an opening for the awl near one edge; a cutting device below said cover and having a pivotal support which projects toward, but not into, the path of the awl; and a cutting portion of said device projecting beyond the end of the support toward the opening.

4. In a pegging-machine, the combination with a straight horn; of a top or cover provided with an opening for the awl, a cutting device transversely movable below said opening; and an oscillating shank for said cutting

device offset with relation thereto and having a pivotal support projecting toward but not into the path of the awl.

5. The combination with the straight horn; of cutter-jaws mounted to oscillate within the said horn, the said cutter-jaws having their ends inclined or offset with relation to their bearing portions; cutters mounted on the tops of said jaws; a horn top or cover having a 10 channel for the said cutters; an opening for the awl above the said channel; and a pivotal support for said jaws projecting toward but not into the path of the awl.

6. The combination with the straight horn

of a cutting device mounted to oscillate in the 15 top of said horn, the cutting portion of said device being offset longitudinally with relation to the bearing portion thereof, and an opening for the awl in line with the offset cutting portion, substantially as described. 20

In testimony whereof I have signed my name to this specification in the presence of two subscribing witnesses.

JOHN F. DAVEY.
